UNITED STATES PATENT OFFICE.

WALTER A. HEINRICH, OF ST. LOUIS, MISSOURI, ASSIGNOR TO W. N. MATTHEWS CORPORATION, OF ST. LOUIS, MISSOURI.

SWITCH.

Application filed July 27, 1925. Serial No. 46,233.

This invention relates to electrical distribution apparatus and particularly to fuse switches and their containing boxes such as are used in high potential transmission lines. 5 The general type of switch box involved is shown in prior Patents, No. 1,288,951 and No. 1,398,335, issued to Claude L. Matthews and myself, December 24, 1918, and November 29, 1921, respectively. 10 The general type of fuse switch involved is shown in prior Patent No. 1,514,210, issued to myself November 4, 1924.

Among the several objects of my present invention may be noted the provision of an 15 improved combination of parts whereby wire connections to a fuse switch may be made at relatively inaccessible points such as on poles and the like without intricate operations of linemen, the provision of a simplified device of the type described which will give positive flow of current under adverse 20 conditions of installation and handling, and one which can withstand long and hard abuse. Other objects will appear in part 25 and will in part be pointed out hereinafter.

The invention accordingly comprises the 30 features of construction, combinations of elements and arrangements of parts, which are exemplified in the description hereinafter in connection with the accompanying drawings, and the scope of the application of which will be indicated in the following claims.

In the accompanying drawings, in which is 35 illustrated one of various possible embodiments of the invention,

Fig. 1 is a vertical section taken from front to rear of the fuse box, showing certain parts in elevation, and in dotted lines alternate positions of certain parts;

Fig. 2 is a vertical section taken on line 40 2—2 of Fig. 1, a lid being shown open, a clip block in disconnected position, and a fuse block removed;

Fig. 3 is a view similar to Fig. 2 showing 45 the clip block in connected position;

Fig. 4 is a vertical section of the fuse block or cartridge;

Fig. 5 is a detail section taken on the line 50 5—5 of Fig. 4;

Fig. 6 is a vertical section of a clip insulator taken on the line 6—6 of Fig. 2;

Fig. 7 is an enlarged plan view of a clip and its insulator;

Fig. 8 is a front elevational detail of a 55 hinge;

Fig. 9 is a side elevation of the hinge of Fig. 8; and,

Fig. 10 is a bottom plan view of the switch box as a whole.

Similar reference characters indicate corresponding parts throughout the several views of the drawings.

Referring now more particularly to Figs. 1 to 3, there is illustrated at numeral 1 the back of the switch box. Sides 3 are made fast 60 to the back 1. The upper edges of the sides slope rearwardly and a rearwardly sloping waterproof cover 5, preferably fibre, is screwed to the top edges of the back and sides. The cove 5 overhangs the box at all points to 65 form eaves. A partially open bottom portion 7 is formed in the box.

On the sides 3 beneath the eaves of the cover 5 are screwed forwardly extending purchase pieces 9 (Fig. 9). These extend forwardly past and flush with a front door 11. The door 11 has screwed to its edges vertical purchase pieces 13, crimped at 15 to accommodate the passage of said pieces 9 (Fig. 8). The pairs of pieces 9 and 13 intersect one 70 another in side elevation and at the point of intersection are provided with holes drilled in line. A set of drive screws 17 are horizontally passed through the pairs of holes and into the door 11 whereby the door 11 is ruggedly and economically hinged to the said box at the top front edge thereof. The improved purchase on the box of the hinges, formed as described, is evident.

The door 11 swings forwardly on the hinge 75 pieces and at its lower end is provided with an inwardly extending portion 7^a of said bottom 7 (see Fig. 10). The portions 7 and 7^a of the bottom cooperate when the door 11 is closed to close the lower end of the box 80 except at the open slot 19. This slot 19 permits the lower open end 21 of a fuse block or cartridge 23 to protrude from the box for purposes to be described. The slot is cut 85 partially in the piece 7 and partially in the piece 7^a.

A clip 25 serves to hold the door 11 normally closed. It comprises a U-shaped piece of spring metal 16 screwed to the door and having sideward legs 18. The legs 18 are provided with holes 20 which yieldingly engage the heads of screws 22 placed in the sides 3 of the box.

To hold the door in open position while the fuse carrying member 23 is being removed 100 105 110

or replaced or other operations performed, there is provided a spring detent member 27, one end of which is pivotally connected to a suitable bracket 29 on the door 11 (Fig. 1). This detent member 27 is provided with a slot 31 through which passes a pin or stud 33, the same being seated in one end of the side wall 3. The inner end of this detent is rebent to form a spring finger 35, the end 10 of which bears against the inner face of said detent 27, and thus when the door is swung into open position, as shown by dotted lines in Fig. 1, the head of the stud 33 will ride into position beneath the spring finger as 15 shown in Figs. 2 and 3, and thus the door will be yieldingly restrained in open position.

The box as a whole is held in position by brackets 37 fastened to the back 1.

Within the box are provided several novel 20 features for making quick connections to a clip block and fuse block or cartridge.

On the back 1, within the box is provided 25 an adjustable clip block 39. This block is provided with slots 41 for the loose passage therethrough of bolts 43. The bolts pass 30 through holes in the back 1 of the box and are provided on the outside with washers and nuts. The heads of the bolts 43 are larger than the slots 41, and hence by tightening the nuts may be caused to clamp the clip block 35 against the back 1 of the box. Likewise loosening of the nut will permit the clip block 39 to be adjusted vertically.

The clip block 39 comprises the relatively 35 thin bar into which said slots 41 are cut. It carries at each end a clip insulator 45. The insulators 45 are hollow and are adapted to receive centrally thereof plastic insulating material such as shown at 47 for purposes of 40 molding the insulators to said block 39 (see Fig. 6). Integrally formed buttons 49 on both ends of the block 39 serve to grip the insulators to the block when the plastic molding material dries.

45 At the upper end of the insulators 45 are molded clip assemblies 51.

The clip assemblies 51 each comprise a grooved nut 63 which prevents withdrawal or 50 twisting of the assembly from the insulator 45 after it has once been molded therein. Riveted to said nut 63 by means of a rivet 65 are clip pieces 67 and a wire terminal 69. The process of riveting makes an absolutely 55 positive electrical connection between the terminal 69 and clips 67, not attainable by a mere bolting together of these parts.

The terminal 69 comprises a flat plate 71 which receives the rivet 65 and lays between the legs of the clips 67. Cast with the plate 60 71 are two branching terminal wire connectors 73, located angularly with regard to the vertical center line of the box. The connectors 73 are adapted to receive wire ends 65 therein and are provided with the usual set screws for holding the wires. Between the

inner open ends of the hollow connectors 73 are cast two solder troughs 75 separated from one another by a wall 77. The plate 71, the troughs 75, the dividing wall 77 are all integrally cast, preferably of brass or other 70 non-corroding metal and with which a soldered joint may easily be made.

It will be noted that the nut 63 clip 67, and the described terminal assembly are riveted together as a unit and it is this unit which is 75 molded on the top of the insulator 45. The clip block 39 carries an insulator assembly such as shown in Fig. 6 at each end thereof. It is evident that the clip block carrying the insulator assembly which includes the clips 80 67 may be moved vertically into any of various positions. The purpose of this is as follows:

When leading wires into the switch box it is necessary to provide ample insulation 85 therefor. Hence the sides 3 of the box are drilled in a slanting fashion as shown in Figs. 2 and 3 at the numeral 79. These holes 79 are adapted to receive cylindrical insulators 81 from the inside of the box. The insulators 81 are provided with shoulders 83 which prevent their sliding out of the box and they are pointed downwardly to prevent moisture from entering the box.

The parts of this device are so arranged 90 that when the clip block 39 is in its lowermost position as illustrated in Fig. 2, the insulator and clip assemblies 45 do not interfere with the entering of the insulator tubes 81 into their respective holes 79. (See dotted lines, Fig. 100 2.) However after the insulator tubes 81 have been entered into their respective holes 79 the clip block and all that it carries may be slid upwardly to the position shown in Fig. 3, whereupon the wire terminal pieces 73 are 105 aligned with the centers of the bores of the insulators 81. The dotted and full lines of the insulators shown in Fig. 2 illustrates the manner in which they are applied to the box. After positioning the clip block, as described, 110 the nuts of bolts 43 may be tightened to hold said block in its proper position.

After alignment between terminals 73 and insulators 81 is attained as shown in Fig. 3 wires 85 may be pushed through the insulators 81 directly into the wire terminals 73 and the ends put into troughs 75 without bending or crimping the wire. Solder may then be applied to the wire and into one of the troughs 75 thereby making an excellent electrical connection.

It will be noted in Figs. 2 and 3 that only 125 two insulator tubes 81 are being used, one on each side of the box. This presupposes that the box as a whole is to be put into an electrical line, one side of which enters one side of the box and the other side of which leaves the opposite side of the box. The provision of four holes 79 as illustrated, and the provision of four wire terminals 73 makes the de- 130

vice perfectly universal and of either the right or left hand type. The pair of holes shown out of use in Figs. 2 and 3 may have the insulators 81 applied thereto if so desired, whereby the relative positions of the wire leads are changed. As shown in the drawings, the pair of holes 79, not in use are covered by weatherproofing plates 78. So far it is evident that the clips of the clip block 10 form the line terminals within the box. It now remains to describe the fuse connector for these terminals.

Figs. 1 and 6 show that the insulators 45 have their outer surfaces corrugated. Referring to Fig. 1 there is shown clamped to the lower insulator block 45 a downwardly extending hinge 83. One of the said corrugations prevents movement of the clamp along the insulator. The hinge 83 has 20 hingedly formed therewith an arm 85 which is adapted to swing from a horizontal to a vertical position. The arm 85 is provided with a slot 87 (Figs. 2 and 3). The slot 87 is adapted to removably receive the lower 25 end 21 of the fuse carrying member 23 (Fig. 1). Hence the fuse carrying member 23 may be swung from a vertical to a horizontal position with the arm 85 when said arm swings from its horizontal to its vertical 30 position respectively.

Referring now to Fig. 4, the fuse carrying member 23 will be described. It comprises two, preferably fibre, insulating tubes held together by a lower band 91, and a central 35 band and metallic terminal piece 93. At the upper end of the longer of the two tubes 89 is provided another metallic terminal piece 95. The terminal pieces 93 and 95 are adapted to receive in electrical connection 40 therewith a fuse wire 97. A detail showing the means for making the connection is shown in Fig. 5. The ends of the wire are clamped to the sides of the terminal pieces 93 and 95 by means of set screws 99. Hence 45 it is obvious that the fuse wire may be removed from the tubes merely by loosening the set screws 99 and withdrawing it from the open lower ends of the tubes. The fuse carrying block is applied to the aforesaid 50 terminal clips 67 of the fuse blocks 45 by placing its lower end 21 in the slot 87 of the arm 85. Then by swinging the fuse carrying member 23 with the arm 85 vertically, the terminal pieces 93 and 95 of the member 23 are 55 thrown into contact with the clips 67 and hence electrical connection is made between the respective pairs of clips on the insulators 45 at the two ends of the clip block 39. These clips are the line terminals, as described, and 60 are now connected by means of the fuse wire 97.

The complete operation of the box is as follows:

Near the line to which a fuse is to be applied 65 is hung the box. The lineman loosens the

nuts on the bolts 43 thereby permitting the clip block 39 to drop into a lowermost position. The door is opened and it is now possible to apply a pair of insulating tubes 81 to the holes leading out of the box. These tubes 70 are applied from the inside as described.

Next the clip block 39 is raised into its Fig. 3 position, whereupon the nuts on bolts 43 are tightened thereby clamping the clip block assembly in place. 75

The line wires 85 are then passed through the insulators 81, from the outside, into the wire terminals 73 and soldered in the troughs 75. The screws in the terminals are tightened to take external strains from the soldered connections. It should be noted that only two insulators 81 and four terminal screws are supplied with a box. It is therefore either of the left hand or right hand 80 type depending upon how said screws and insulators are applied. However it is to be observed that four lead wires, four insulators 81 and eight screws to fasten four lead wires may be employed if an operator sees fit to lead two wires to each set of clips. Furthermore two wires may be led into one side of 85 the box only, if desired.

Next a fuse block or fuse carrying member or cartridge 23 is fitted with a fuse wire 97. The member 23 has its lower end 21 inserted into the slot 87. The block 23 is then in its dotted line position shown in Fig. 1. After this the block 23 is rotated up with the arm 85 and the terminal pieces 93 and 95 of the fuse engage the sets of spring clips 100 67 thereby closing the circuit through the fuse wire 97. The clips 67 are composed of 90 copper or other conducting material.

In order to make the device safe for operation by a lineman, a bridge portion 101 is 105 cast with the upper terminal piece 95 which may be engaged by a hook of an insulated tool carried by said lineman, whereby he is not required to apply his bare hands to the fuse carrying member 23, either for engagement or disengagement thereof. 110

When a fuse wire 97 burns the violent accompanying expansion of heated gases, projects all inflammable and other undesirable material from the tubes 89 to the outside of 115 the box. The lower tube ends extend from the box when the clip block 39 is in its uppermost position.

After inserting the fuse block 23, as described, the door 11 is closed and the device 120 is in operation. It is entirely weatherproof, compact but rugged in construction and free from danger to an operator. Its action is electrically positive because of the improved means for riveting the line terminals 73 and 125 the terminal clips 67 together.

From the above it will be seen that the several objects of the invention are attained and other advantageous results achieved.

As many modifications of the embodiments 130

above illustrated might be made without departing from the spirit or scope of the present invention; it is intended that the above description and accompanying drawings and 5 claims shall be interpreted as illustrative and not in a limiting sense.

I claim:

1. A safety switch comprising a box, movable and relatively spaced line terminals therein, insulating members passing through the box and adapted to be applied from within the box, said relatively spaced terminals being adjustably movable without affecting said spacing to permit application of said insulating members.
2. A safety switch comprising a box, slidably movable spaced line terminals therein, insulators adapted to be positioned in the walls of said box when the terminals are in one position, said terminals aligning with the positioned insulators in another position, whereby unbent wires may pass through the insulators to the terminals, said terminals comprising cylindrical portions and set screws therefor 25 for the passage and clamping of wire there-through and solder troughs adjacent the said cylindrical portions for soldering the said wires.
3. A universal safety switch comprising a box having a pair of holes in each side of said box oppositely spaced, a pair of insulators adapted to be passed one each through one of a set of oppositely spaced holes, integral pairs of movable spaced line terminals within the 35 box adapted to be moved to permit application of said insulators and adapted to be moved to prevent removal of said insulators and to align with said insulators whereby unbent wires may be passed through said insulators to said terminals, said terminals each comprising two clamping portions adapted to cooperate with a wire coming in either hole of a pair of said holes and cover pieces for such of 40 said holes as are not occupied by insulators.
4. A switch comprising a box, a movable clip block within the box carrying line terminals,

nals, insulators adapted to be positioned through the side walls of said box when said block is in one position, said block aligning its line terminals with said positioned insulators 50 in another position thereof, a hinge on the clip block, adapted to removably carry a fuse block which engages said line terminals when swung on the hinge, the line terminals comprising aligning connectors for wires passing 55 through said insulators, integrally formed troughs for soldering said wires, and clips riveted to said troughs and connectors for receiving the engaging portions of said fuse block. 60

5. A universal safety switch comprising a box having a pair of holes in each side of said box oppositely spaced, a pair of insulators adapted to be passed one each through one of a set of oppositely spaced holes, integral pairs 65 of moveable spaced line terminals within the box adapted to be moved to permit application of said insulators and adapted to be moved to prevent removal of said insulators and to align with said insulators whereby unbent 70 wires may be passed through said insulators to said terminals, said terminals each comprising two clamping portions adapted to cooperate with a wire coming in either hole of a pair of said holes and cover pieces for such of 75 said holes as are not occupied by insulators.

6. A safety switch comprising a box, movable and relatively spaced line terminals therein, insulating members passing through the box and adapted to be applied from within 80 the box, said relatively spaced terminals being adjustably movable without affecting said spacing to permit application of said insulating members, a hinged fuse block adapted to engage said terminals, and adapted to move 85 therewith, said box having an opening therein adapted to permit said fuse block to protrude therefrom and be movable therein.

In testimony whereof, I have signed my name to this specification this 24th day of July, 1925.

WALTER A. HEINRICH.
